(57) **CLAIM**

The ornamental design for a shoe, as shown and described.

DESCRIPTION

FIG. 1 is a front, left, bottom perspective view of a shoe showing our new design;

FIG. 2 is a rear, right, bottom perspective view thereof;

FIG. 3 is a bottom view thereof;

FIG. 4 is a top view thereof;

FIG. 5 is a right side view thereof;

FIG. 6 is a left side view thereof;

FIG. 7 is a rear view thereof; and,

FIG. 8 is a front view thereof.

In the drawings, the dash-dash broken lines show portions of the shoe that form no part of the claimed design. The dash-dot broken lines represent the bounds of the claimed design that form no part of the claimed design.

1 Claim, 5 Drawing Sheets
